UNITED STATES PATENT OFFICE.

SIMON J. DAYKIN, OF NEW YORK, N. Y.

NON-REFILLABLE BOTTLE.

SPECIFICATION forming part of Letters Patent No. 702,709, dated June 17, 1902.

Application filed November 12, 1901. Serial No. 81,980. (No model.)

To all whom it may concern:

Be it known that I, SIMON J. DAYKIN, a subject of the King of Great Britain, residing in the city, county, and State of New York, 5 have invented a new and useful Improvement in Non-Refillable Bottles, of which the following is a specification.

My invention consists of an improved construction of a non-refillable bottle, wherein 10 provision is made for enabling the contents of the bottle to be readily discharged therefrom when the bottle is inverted and means provided for preventing the improper or fraudulent refilling of the same, whereby a 15 bottle of this character after the contents thereof have been once used cannot be refilled.

To the above ends my invention provides for an improved construction of bottle which 20 is adapted for holding valuable liquids and capable of not being refilled, thereby avoiding any liability of the imitation of said valuable liquid being sold in the established bottles.

25 The invention also consists of a novel construction of cage or retaining device for the spring-pressed valve or its equivalent employed, whereby the valve will always be retained in the proper position, said cage being 30 provided with foraminous covering, whereby the same serves the dual function of a strainer and also of an inclosing device for the valve and its adjuncts.

It further consists of novel details of construction, all as will be hereinafter fully set 35 forth, and particularly pointed out in the claims.

Figure 1 represents a longitudinal sectional view of a non-refillable bottle and its adjuncts embodying my invention. Fig. 2 represents a vertical sectional view of a portion 40 of the combination strainer and cage employed to inclose the spring-pressed valve and its adjuncts. Fig. 3 represents, on an enlarged scale, a plan view of the stopper-body and its adjuncts in detached position. Fig. 4 represents a vertical sectional view on line $x-x$, Fig. 3. Fig. 5 represents a side elevation of Fig. 4. Figs. 6 and 7 represent 45 detail views of the cage and straining device employed in detached position. Fig. 8 represents a plan view of a modified construc-

tion of the stopper-body seen in Fig. 3. Fig. 9 represents a sectional view, partly in elevation, of the stopper-body seen in Fig. 8. 55 Fig. 10 represents a portion of the cage and straining device adapted to be employed in conjunction with Fig. 8. Fig. 11 represents a perspective view of the preferred form of tool employed for inserting the stopper-body 60 seen in Figs. 3, 4, 5, 8, and 9 in position.

Similar numerals of reference indicate corresponding parts in the figures.

Referring to the drawings, 1 designates a non-refillable bottle, the same having the 65 neck 2 provided with the recess or seat 3 therein, wherein is located the ring 4, of rubber or other suitable resilient material, said ring having the inclined or upwardly-diverging walls 5, which are adapted to coact and engage with the inclined walls 6 of the stopper-body 7, the latter being provided with the upper and lower flanges 8 and 9, which are adapted to project over the upper and lower portions of said ring 4. The stopper-body 7 75 has the opening 10 therethrough, which is provided with the transverse strip 11, which has the opening 12 therethrough, through which passes the stem 13 of the valve 14, which is adapted to contact with the valve-seat 15, 80 said valve being held normally upon its seat by means of the spring 16, the lower extremity of the latter contacting with the valve, while the upper extremity of said spring contacts with the top of the cage 17, the latter 85 being formed by means of the U-shaped portion or strip 18, which is covered with gauze 19, the lower extremities of said strips 18 being provided with the feet 20, which are adapted to enter the recesses 21 in the stopper-body 7, said recesses being provided with the upward extensions 22, in which the lower portions of the legs of the strip 18 are adapted to rest. The spring 16 is suitably guided and retained in position by means of the upward extension 23, which projects from the valve 14. In lieu of gauze I may use any other foraminous material. 90

24 designates the outer stopper for the bottle, which may be of the usual construction. 100

The manner of assembling the parts is as follows: The valve 14 is first placed upon its seat and the spring 16 placed in position thereon, after which the cage 17 is placed

over the valve and upon the stopper-body in the manner seen in Fig. 1, the feet 20 and the lower portions of the strip 18 being inserted in the recesses 21 and 22. The ring 4 having been placed in position, the stopper-body, carrying the valve, spring, and cage, is slipped into the neck of the bottle, and the parts now assume the position seen in Fig. 1. When it is desired to empty the bottle, the stopper 24 is removed, and upon the inversion of the bottle the contents will flow therefrom in the usual manner, it being understood that the spring 16 is of sufficient tension so as to permit the unseating of the valve 14 according to requirements when the bottle is inverted, the gauze 19 serving as a strainer for the liquid during its flow from the bottle. The bottle having been once emptied, it will be apparent that the same cannot be improperly or fraudulently refilled, since if any attempt is made after the removal of the stopper 24 such action will only cause the valve 14 to be more firmly seated, the seating of said valve being positively assured by means of the spring 16.

It will of course be apparent to those skilled in the art that changes may be made in the manner of constructing and assembling the stopper-body 7 and its adjuncts, since, if desired, I may employ the stopper-body 28, which is constructed in all substantial respects like the body 7, except that said body 28 instead of being provided with grooves 22 and recesses 21 diametrically opposite to each other, as shown in Figs. 3 to 5, inclusive, may be provided with the slots 26, which terminate in the enlarged recesses 27, said slots extending parallel to each other, as will be understood from Figs. 8 and 9, and being adapted to receive the cage 27^x, which is constructed substantially the same as the cage 17, already described, except that the feet 28^x thereof extend laterally and parallel to each other from the curved strip 29, which corresponds to the curved strip 18, already described. The manner of assembling the modified construction of cage and stopper-body will be understood from Figs. 8 and 10, it being understood that the feet 28^x are slipped into the enlarged recesses 27, the parts when assembled appearing substantially as indicated in Fig. 1, as is evident.

In Fig. 11 I have shown a convenient form of tool 30 for inserting the stopper-body 7 or 28 in position, said tool having the handle 31, from which depend the arms 32, which terminate in the rings 33, which have the openings 34 therein, whereby said tool can be inserted in the neck of the bottle above the stopper-body 7 for the purpose of pushing the latter and its adjuncts into the position seen in Fig. 1.

It will be apparent that slight changes may be made by those skilled in the art which will come within the scope of my invention, and I do not, therefore, desire to be limited

in every instance to the exact construction herein shown and described.

Having thus described my invention, what I claim as new, and desire to secure by Letters Patent, is—

1. The combination with the neck of a bottle having an enlarged recess therein, of a ring seated in said recess, a stopper-body adapted to engage said ring, a cage composed of gauze and having feet at its lower portion adapted to engage suitable recesses in said stopper-body, a valve-seat in the upper portion of said stopper-body, a valve-stem depending from said valve and a guide for said valve-stem, in combination with a spring interposed between the top of said valve and said cage, a wall of the latter serving as a strainer for the liquid contained in the bottle during the act of emptying the same. 85

2. In a non-refillable bottle, a stopper-body having an opening therethrough and a valve-seat in its upper portion, a stem depending from said valve, a guide within said stopper-body for said stem, a cage inclosing said valve and consisting of a strip provided with feet at its lower portion, interlocking devices common to said feet and stopper-body and a foraminous covering supported on said strip, an extension projecting upwardly from said valve, and a spring surrounding said extension and interposed between said valve and the top of said cage. 95

3. In a non-refillable bottle, a stopper-body having an opening therethrough and a valve-seat in its upper portion, a stem depending from said valve, a guide within said stopper-body for said stem, a cage inclosing said valve and consisting of a strip provided with feet at its lower portion, interlocking devices common to said feet and stopper-body and a foraminous covering supported on said strip, an extension projecting upwardly from said valve, and a spring surrounding said extension and interposed between said valve and the top of said cage, in combination with the neck of a bottle having an enlarged recess therein, and a ring seated in said recess and supporting said stopper-body. 105

4. In a non-refillable bottle, a stopper-body having an opening therethrough recesses therein and a valve-seat in its upper portion, a stem depending from said valve, a guide for said stem, a cage inclosing said valve and consisting of a strip provided with enlarged feet at its lower portion which are adapted to engage and interlock with said recesses in said stopper-body, and a foraminous covering supported on said strip. 110

5. In a non-refillable bottle, a stopper-body having an opening therethrough recesses therein and a valve-seat in its upper portion, a stem depending from said valve, a guide for said stem, a cage inclosing said valve and consisting of a strip provided with enlarged feet at its lower portion which are adapted to engage and interlock with said recesses in 125

said stopper-body, and a foraminous covering supported on said strip, in combination with the neck of a bottle having a recess therein and a ring seated in said recess and supporting said stopper-body.

5. In a non-refillable bottle, a stopper-body having an opening therethrough, recesses therein and a valve-seat in its upper portion, a cage inclosing said valve and consisting of

a strip having feet interlocking with said recesses in said stopper-body and a foraminous covering supported on said strip and inclosing said valve, said covering serving as a strainer during emptying of the bottle.

10 SIMON J. DAYKIN.
